(57) **CLAIM**

The ornamental design for an electric wheelchair as shown and described.

DESCRIPTION

FIG. 1 is a top, front perspective view of an electric wheelchair showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a bottom, rear perspective view thereof;

FIG. 9 is an enlarged detail view taken from portion 9 of FIG. 1;

FIG. 10 is an enlarged detail view taken from portion 10 of FIG. 1; and,

FIG. 11 is an enlarged detail view taken from portion 11 of FIG. 2.

The broken lines depict portions of the electric wheelchair that form no part of the claimed design.

The broken lines encircling portions of the electric wheelchair in FIGS. 1 and 2 and illustrated in enlarged views in FIGS. 9-11 form no part of the claimed design.

1 Claim, 11 Drawing Sheets
